(57) **CLAIM**

The ornamental design for a dumbbell support cradle, as shown and described.

DESCRIPTION

FIG. 1 is a rear perspective view of the dumbbell support cradle showing my new design;

FIG. 2 is a side elevation view thereof;

FIG. 3 is a rear elevation view thereof;

FIG. 4 is a front elevation view thereof;

FIG. 5 is a top plan view thereof; and,

FIG. 6 is a bottom plan view thereof.

The broken lines depict environmental structure and do not form a part of the claim.
